UNITED STATES PATENT OFFICE.

JOHN B. NEALE, OF BATTLE CREEK, MICHIGAN, ASSIGNOR OF ONE-HALF TO FRED W. GAGE, OF BATTLE CREEK, MICHIGAN.

OVERLAY FOR HALF-TONE PRINTING.

1,178,869.

Specification of Letters Patent. Patented Apr. 11, 1916.

Application filed August 14, 1915. Serial No. 45,580.

To all whom it may concern:

Be it known that I, JOHN B. NEALE, a citizen of the United States, residing at Battle Creek, in the county of Calhoun and State 5 of Michigan, have invented certain new and useful Improvements in Overlays for Half-Tone Printing; and I hereby declare that the following is a full, clear, and exact description thereof, reference being had to the 10 accompanying drawings, which form part of this specification.

This invention or discovery relates to the art of printing, and has particular reference to the producing of fine high grade illus- 15 trated work commonly called "half-tone" printing; and the object of the present invention is to enable such "half-tone" printing to be effected in a superior manner, and to be successfully produced upon grades of 20 paper, such as uncoated book paper and ordinary newspaper stock, which it has heretofore been considered impractical to use for such printing; but my invention will enable excellent results to be produced from 25 ordinary half-tone cuts on the commonest grade of newspaper stock.

Another object is to reduce the amount of labor, time and skill required in "making ready" the press for such kind of printing, 30 and to enable superior half-tone printing to be produced on ordinary presses.

The principal and basic feature of my invention or discovery is that by making or providing overlays with a measurably yielding cushioned or resilient surface, as compared with the hard, unyielding overlays heretofore employed, greatly superior results are obtained in printing, such results being primarily due to the said resilient or 40 cushion surface of the overlay.

The invention or discovery may be practically utilized in two ways as follows:

First, by providing any of the ordinary known makes of overlays with a resilient or 45 cushioning surface, which may, as applied to such overlays, be formed of a thin sheet of soft rubber vulcanized, or of an equivalent cushioning material, applied over the face of the overlay; so that all the points and shades of gradations of pressure which 50 would be ordinarily caused by the overlay are transmitted through the surface with a degree of resiliency or cushioning that is not afforded by the hard overlays; and such

cushioning surface noticeably compensates 55 for any minute surface irregularities in the paper or material being printed, which a hard unyielding surface overlay could not do, and this cushioning or compensating quality of the overlay is particularly im- 60 portant when printing poor grades of paper, such as newspaper. Such a resilient surface or sheet may be attached directly to the overlay by any suitable means, or it may be attached to the cylinder packing directly 65 opposite the overlay so as to be properly positioned relative thereto. Where a yielding cushion surface, such as rubber, is applied to a metallic or other hard overlay, it may be attached thereto by vulcanizing or 70 by means of paste, glue, cement or other adhesive, provided that same will not interfere with or prevent the desired resiliency of the surface of the overlay. Such a resili- 75 ent or yielding cushioning surface is applicable to many of the commonly used forms of make-ready, such as the "Gilbert Harris metallic", the so-called "chalk" process, the "Bierstadt-De Vinne", or even the hand-cut paper overlay. The invention 80 when so utilized combines an element of surface resiliency or cushioning with the known forms of hard make-ready usually employed, and will produce superior and hitherto unattainable effects from half-tone 85 plates upon cheap grades of newspaper, or rough-surfaced papers, upon which paper it has previously been impossible to produce impressions of the artistic character and quality produced by the use of my invention, 90 it having heretofore been an accepted maxim of the trade that highly surfaced paper is necessary for fine work in half-tone printing. The invention also obviates the objectionable tendency of the hard-surfaced over- 95 lays to crack, bend, or emboss the paper being printed.

Second: The invention may be utilized by making the overlay itself of resilient or cushioning material, such as rubber. Such an overlay can be produced in the following manner. An inked proof is taken from the original half-tone plate from which it is intended to print, and while fresh is given a coating of bronze, or other suitable finely 10 divided opaque powder. This proof is then used as a negative for printing upon the sensitized surface of a metal plate (properly

2
prepared to take such print by the usual processes employed by metal etchers or engravers) making a reverse print of the same size as the original half-tone plate. The reverse print is then developed and rendered resistant to etching fluid by any suitable method. The plate is then etched to the depth desired in the usual way, and may further be hand-tooled to make changes in 13 its tonal value if desired. A rubber overlay is then made from said etched plate in the usual way by pressure and heat, by any suitable means, and vulcanized sufficiently firm or hard to retain the desired gradations and 15 toning effects of an overlay, but retaining in itself sufficient resilience or yielding properties to give the desired cushioning effect.

In use the overlay provided with a resilient cushioned surface, or the integral 20 silent cushioned overlay above referred to, is placed upon the cylinder or platen of the press, just as an ordinary overlay would be placed. The superior results obtained in 25 printing by using my invention are due to the yielding or cushioning nature of the surface of the overlay, and not to any novelty in the placing of the overlay in the press, or novelty in the mode of operating the press after the overlay is in position.

30 The ordinary overlays are usually "buried" under a varying number of sheets of tympan paper, but I have found that this is not essential when using my invention; that is, were it not for the liability of 35 mechanical injury overlays embodying my invention might be placed on top of the tympan sheets and still be effective for some classes of work. The rubber sheet or cushioning surface is most effective when placed 40 in contact with the hard overlay which it cushions; so that it will transmit directly the varying pressure which the overlay is intended to give.

Upon some classes of printing it might be 45 expedient to interpose more or less tympan paper between the rubber-surfaced overlay and the material to be printed, to obviate any tendency to over-effect. This is common practice with any ordinary make-ready, 50 and in my invention the resilient or cushioned surface when used in combination with hard make-ready will produce the desired effects. Though preferably placed in that position, the cushioning surface does 55 not of necessity have to be in direct contact with the hard overlay. Should the hard overlay be found insufficient a "patch" sheet or auxiliary overlay would naturally be fitted directly upon the original hard 60 overlay as usual in order that the augmented pressure would be placed exactly where desired.

Pressmen will readily understand the 65 many factors which enter into the production of a perfectly printed sheet, which may

require minor changes of make-ready which do not alter the underlying principle of the invention. The resilient or cushioning surface is therefor subject to such variations of position and hardness as will produce the 70 best results, as there is no fixed degree of resiliency or resistance that will yield unvarying results upon all classes of printing.

With such novel overlays I am able to produce beautiful high-grade half-tone printing on ordinary newspaper stock; printing same in an ordinary flat bed or rotary press; and I can produce work which is equal or superior to the work produced by the "Rotogravure" process. When printing on 80 finer grades of paper the work produced is superior in appearance to that produced by any of the heretofore known overlays or processes. The invention may be also employed in printing upon fabrics and other 85 material with greatly improved results, and is also peculiarly adaptable to the production of loose-leaf catalogue illustrations in half-tone without resort to the off-set process of lithography now employed where fine 90 illustrations must be shown upon bond or ledger papers upon which it has hitherto been considered impossible to print successfully half-tone work.

I have conventionally illustrated an overlay embodying the invention and one method of using same in the accompanying drawings; in which—

Figure 1 is a face view of an overlay 3 with a resilient cushioning surface 4; and Fig. 2 is a detail sectional elevation showing how such an overlay is ordinarily arranged when in position for use.

In said drawings the parts are greatly magnified and distorted to facilitate a ready comprehension thereof.

1 designates part of the cylinder or platen; 2 the packing, 3 the overlay and 4 the resilient or yielding surface or sheet superposed on said overlay; 5 the tympan and 6 the draw sheet, this arrangement being such as is customarily employed on cylinders preparatory to printing.

The heavily shaded portions *a*, *b*, *c*, in the example Fig. 1 indicate where the heaviest pressure is imparted through the corresponding portions *a'*, *b'*, *c'*, of the overlay, Fig. 2; and the shaded portions *d*, *e*, Fig. 1 show where medium pressure is imparted through the corresponding portions *d'*, *e'* of the overlay Fig. 2.

I do not herein claim the integral or self-contained resilient cushioning overlay, as that forms the subject-matter of a companion application.

What I claim is:

1. For use in producing high-grade half-tone printing, an overlay provided with a resilient or cushioning surface.
2. For producing high-grade half-tone 120

printing upon ordinary newspaper stock, an overlay having a resilient surface formed of cushioning material.

3. For producing high-grade half-tone printing upon ordinary newspaper stock, an overlay having a resilient cushioning surface.

4. An overlay, having a cushioning surface of rubber:

10 5. An overlay comprising a hard body and a surface of resilient cushioning material, substantially as described.

6. An overlay for the purpose specified, comprising a hard body and a surface 15 formed by a sheet of resilient cushioning material, substantially as described.

7. In combination, an overlay and a resilient cushioning sheet or surface opposite the face of the overlay adapted to transmit 20 the varying pressure which the overlay is intended to give, substantially as described.

8. In combination, an overlay and a resilient sheet of suitable material operatively

positioned opposite the face of the overlay to transmit the varying pressure which the 25 overlay is intended to give, substantially as described.

9. In combination, a hard overlay and a thin resilient yielding cushioning sheet or surface opposite and extending over the face 30 of the overlay for the purpose and substantially as specified.

10. In combination, a hard overlay and a thin resilient sheet or cushioning surface of suitable material operatively positioned opposite 35 the face of the overlay to transmit the varying pressure which the overlay is intended to give.

In testimony that I claim the foregoing as my own, I affix my signature in presence 40 of two witnesses.

JOHN B. NEALE.
